UNITED STATES PATENT OFFICE

2,536,302

CIGARETTE EXTINGUISHER AND
RETRIEVING DEVICE

Leo Mertzel, Flushing, N. Y.

Application February 7, 1947, Serial No. 727,036

3 Claims. (Cl. 131—256)

1

This invention relates generally to a cigarette extinguisher and retrieving device, but more specifically to a device to preserve partially spent cigarettes for subsequent or consecutive use.

The main object of the invention resides in a holder for extinguishing the lighted end of a cigarette and for reserving same for subsequent use so that a partially used cigarette can be relighted and smoked.

A further object of the invention resides in the provision of a cigarette holder having means for extinguishing the lighted end of the cigarette without destroying the form thereof and having means spaced therefrom for receiving the charred portion and the cigarette ash following extinguishment.

Another object of the invention resides in the provision of a cigarette extinguisher and case therefor wherein means are provided for preventing the tar and other products of combustion deposited within the case upon extinguishment of the cigarette from permeating the unused part of the cigarette when the case is closed.

A further object of the invention resides in the provision of a combination cigarette extinguisher or holder and case which is light in weight, easy to manufacture and use and also economical to manufacture.

These objects and other incidental ends of the invention will hereinafter appear in the progress of the disclosure and as pointed out in the appended claims.

Accompanying this specification is a drawing showing a preferred form of the invention wherein:

Figure 1 is a foreshortened view in elevation of the cigarette extinguisher and retrieving device in closed position and enclosing a partially used cigarette.

Figure 2 is an axial sectional view of Figure 1.

Figure 3 is a sectional view of Figure 2 along the plane 3—3 thereof.

Figure 4 is a sectional view of Figure 4 along the plane 4—4 thereof.

In accordance with the invention and the preferred form shown, the device comprises a tubular member 10 having at one open end an internally threaded portion 11 and at the opposite open end having a flared edge 12 for facilitating the entrance of the lighted end of a cigarette 13 therein. A socket 14 is adapted to threadedly engage end portion 11 of tubular member 10 at an externally threaded and reduced neck portion 15. The edge of reduced neck portion 15 adjacent the upper end of the external thread

2

is adapted to receive a grated and removable disc 16 such as a wire mesh which permits penetration of ash and other products of combustion thereto for deposit at the base of socket 14 and as indicated by numeral 17. For this purpose disc 16 is forced through tubular member 10 after socket 14 is in engagement with portion 11.

It is to be noted especially by reference to Figure 2 that the lighted end of cigarette 13 as indicated by numeral 18 is adapted to be rotated in frictional engagement against disk 16 for purposes of extinguishing the cigarette and for freeing the solid products of combustion thereof.

Sufficient clearance is provided between the sides 19 of cigarette 13 and the inner walls of tubular member 10 for escape of the gaseous products of combustion. A cap member 19 is applied to tubular member 10 to enclose the device by engagement of the side walls 20 thereof with the peripheral edge 21 of the flared portion 12. Cap 19 as shown engages the edge 21 in a peripheral groove 22, and for this purpose the side walls 20 are somewhat resilient for application to and removal from edge 21.

25 The socket 14 is removable for cleaning purposes. Cap 19 which may or may not be used aids in the extinguishing of the lighted end 18 of the cigarette by cutting off the supply of air from tubular member 10 when the cigarette is extinguished frictionally. For frictional extinguishment of cigarette 13 at the lighted end 18, slight downward pressure may be applied during rotation to avoid crushing and spreading of the cigarette tobacco adjacent the lighted end.

30 35 The solid products of combustion fall through the disk 16 and thus are not in contact with the extinguished cigarette so that upon reuse of the partially spent cigarette there is absent the characteristic stale taste and odor.

40 The device is normally in upright position with socket 14 at the bottom so that ash 17 within socket 14 does not contaminate end 18 of the cigarette through disc 16 when the device is carried about.

45 The device may be made of any material such as plastic, wood or metal and it is understood that minor changes and variations in the material, location, integration and size of parts may be resorted to without departing from the spirit 50 of the invention and the scope of the appended claims.

I claim:

1. A portable cigarette extinguisher and retrieving device consisting of a tubular member 55 open at both ends, a receptacle of the same ex-

ternal diameter as said tubular member removably engageable with one of said ends, a screen forming the top wall of the receptacle, the other of said ends having a flared peripheral lip and a cover member engageable with said lip. 5

2. A portable cigarette extinguisher and retrieving device consisting of a tubular member open at both ends, a receptacle of the same diameter as said tubular member removably engageable with one of said ends, and a removable screen forming the top wall of the receptacle and frictionally held by the tubular member adjacent the base of the tubular member to serve as a rubbing surface and as a grating for the lighted end of the cigarette. 15

3. A portable cigarette extinguisher and a retrieving device consisting of a tubular member open at both ends, a receptacle of the same diameter as said tubular member removably engageable with one of said ends, a removable screen forming the top wall of the receptacle and frictionally held by the tubular member adjacent the base of the tubular member to serve as a rub- 20

bing surface and as a grating for the lighted end of the cigarette, the other of said tubular ends having a flared peripheral lip and a cover member engageable with said lip.

LEO MERTZEL.
